UNITED STATES PATENT OFFICE.

THOMAS E. CARPENTER, OF PROVIDENCE, RHODE ISLAND.

ATTACHMENT FOR CIGAR-MACHINES.

SPECIFICATION forming part of Letters Patent No. 665,177, dated January 1, 1901.

Application filed October 10, 1900. Serial No. 32,637. (No model.)

To all whom it may concern:

Be it known that I, THOMAS E. CARPENTER, a citizen of the United States, residing at Providence, in the county of Providence and 5 State of Rhode Island, have invented certain new and useful Improvements in Attachments for Cigar-Machines, of which the following is a specification, reference being had therein to the accompanying drawings.

10 Like letters indicate like parts.

Figure 1 is a view of a cigar-machine having my improvement thereon. In this figure the machine is shown partly in front elevation and partly in vertical longitudinal section on the axial line of the upper main roller. Fig. 2 shows in section on said line one of the conical rollers, the cap and part of the upper main roller, and in elevation the ball-joint, the end of the supporting-finger on which the 15 end of the conical roller is mounted, and also the yielding seat-block, which aids in the formation of the pointed end of the cigar. Fig. 3 is a perspective view of said seat-block and the spring on which the same is supported 20 in position. Fig. 4 is a top plan view of the ends of the two lower main rollers and their companion conical rollers, the bracket supporting the ends of said conical rollers, and the yielding seat-block in position between 25 and beneath said conical rollers. Fig. 5 is a front elevation of said cigar-machine. Fig. 6 is an end elevation of the same.

My invention is a device adapted to form the pointed end of the cigar and is shown as 30 applied to the improved cigar-machine described in Letters Patent of the United States No. 639,663, granted to me December 19, 1899.

Said invention consists of the novel construction and combination of the several elements, as hereinafter particularly described, and as set forth in the claims.

I will describe so much of my said patented machine as will render intelligible the construction and operation of the devices which 45 constitute my present invention.

In a standard A are mounted the journals of three main rollers B, C, and D, concave and fluted, as shown. At each end of these rollers in a socket thereof is mounted a ball 50 E, having a screw-threaded stem F. A tubular cap G upon said end of the main roller serves to confine the ball E in said socket.

The main rollers have companion conical rollers H H' H'', respectively. Each of these conical rollers is concaved and fluted and made 55 with an axially-directed screw-threaded bore in its larger end to receive the screw-threaded stem F of the ball E and also with a socket in the smaller end. The conical rollers H H', which are companions of the main rollers C 60 and D, are mounted at their smaller ends by the sockets therein upon the brackets I, and the conical roller H, which is the companion of the top main roller B, is mounted at its smaller end by the socket therein upon the 65 bent-up end of the finger J, which is supported on the end of the rod K. The standard A has a curved slot (see Fig. 6) in which the journal of the roller B is mounted and movable, and a handle M, having its lower end 70 bifurcated to embrace the roller B in a circumferential groove thereof, as shown in Fig. 1, is adapted to swing said roller B (and its companion conical roller, as also the rod K, which is fastened to said handle) out of the position which said roller B normally has to allow 75 the cigar-bunch to be placed upon the lower rollers C and D, and then the roller B is returned to its operative position by means of the handle M.

The driving-shaft of the machine is shown at N and has a gear O thereon. Each of the main rollers has a gear on the end of its journal engaging with said gear O, as seen at P, Q, and R. On the shaft N is a fixed clutch 85 member S and a spiral spring T. A pulley U, which is driven by a belt V, has a clutch member W attached thereto; but said pulley and its clutch member are loose upon said shaft. The outer end of the shaft N is mounted in a support X. When the pulley U and its clutch member W are slid along the shaft N by a handle or shipper, (not shown,) the clutch members S and W engage, whereupon the driving-shaft is rotated by the power of 90 the belt V, and the rollers B C D H H' H'' are revolved by reason of the engagement of the gears O, P, Q, and R. When the handle or shipper is moved in the opposite direction, the spiral spring T separates the clutch members S and W and the machine stops its operation. Upon this machine so operated I place under the top conical roller H (see Figs. 1 and 2) and between the lower conical roll-

ers H' H" (see Fig. 4) a yielding seat-block *a*, (shown in perspective in Fig. 3,) adapted to receive the lower portion of the bent finger *J*, as illustrated in Figs. 1 and 2. This 5 yielding seat-block is curved and tapering in form and has at its upper smaller end a concaved seat with its sides upturned, as seen in Fig. 3. It is supported upon the end of a spring *b*, to one end of which it is attached 10 by the screw *c*, and the other end of the spring is held upon the standard or end of the machine by the bracket *I* and clamping-screw *d*. As shown in Figs. 1 and 2, the outer smaller 15 end of the upper conical roller *H* abuts the inner edge of the concave seat *t* of said block *a*. When the cigar-bunch has been properly formed between the said rollers B C D and their companion conical rollers by the rotation of said rollers, a leaf-wrapper is wound 20 thereon, being laid angularly upon the table *r* and started to cover the pointed end of the cigar and thereafter wound angularly on the cigar-bunch to the opposite end of the same. The edge of said wrapper at the point of contact 25 of the conical roller *H* and the yielding block *a* (see Fig. 2) is turned inwardly, and the first fold of the wrapper passing over said turned-in end binds the same in position, thus forming a smooth covered end at the 30 point of the cigar. The spring *b* keeps the block *a* snugly in contact with the smaller end of the conical roller *H*. The roller *H* when swinging into its operative position slips its said end over the lip *s* into the concave seat *t*, but is held against further movement 35 in said direction by the upward extension *u*, all as shown on an enlarged scale in Fig. 3. Any unevenness or irregular bunching of the filling which might deflect or tend 40 to spring the roller *H* out of its true working position against the tension of the spring-rod *K* is compensated for by the action of the spring *b*, which causes the block *a* to follow up said roller *H* and compels the constant 45 seating of the end of said roller in the seat *t* of said block, thus insuring the proper covering of the smaller end of the cigar-bunch by the leaf-wrapper.

I claim as a novel and useful invention and 50 desire to secure by Letters Patent—

1. In a cigar-machine, the combination of three rollers with converging ends, one of said rollers being located midway between the other two rollers but in a higher plane, a 55 properly-mounted spring-finger whose lower extremity is bent and forms a support for said upper roller, two fixed brackets or supports on which, respectively, said two lower rollers are mounted, a spring fastened at one 60 end to a fixed support and a block mounted on the free end of said spring and provided with a concave seat at the end thereof adapted to receive the bent portion of said spring-finger and to abut the end of said upper roller, 65 said block being located beneath said upper roller and between the two lower rollers, substantially as described.

2. In a cigar-machine, the combination of three main rollers, one of which is located midway between the other two but in a higher 70 plane, companion conical rollers for said main rollers, respectively, and having converging ends, a ball-and-socket connection between each of said main rollers and its companion conical roller, a properly-mounted spring-finger whose lower extremity is bent and forms a support for the upper conical roller, two 75 fixed brackets or supports on which, respectively, the two lower conical rollers are mounted, a spring fastened at one end to a fixed support and a block mounted on the free end of said spring and provided with a concave seat at the end thereof adapted to receive the bent portion of said spring-finger and to abut the end of said upper conical roller, said block being located beneath said upper conical roller and between the lower conical rollers, substantially as shown.

3. In a cigar-machine, the combination of three rollers with converging ends, one of said rollers being located midway between the other two rollers but in a higher plane, a properly-mounted spring-finger whose lower extremity is bent and forms a support for said upper roller, two fixed brackets or supports 90 on which, respectively, said two lower rollers are mounted, a spring fastened at one end to a fixed support and a curved tapering block mounted on the free end of said spring and provided with a concave seat at the end thereof adapted to receive the bent portion of said spring-finger and to abut the end of said upper roller, said block being located beneath said upper roller and between said lower rollers, substantially as specified.

4. In a cigar-machine, the combination of three main rollers, one of which is located midway between the other two but in a higher plane, companion conical rollers for said main rollers, respectively, and having converging ends, a ball-and-socket connection between each of said main rollers and its companion conical roller, a properly-mounted spring-finger whose lower extremity is bent and forms a support for the upper conical roller, two 100 fixed brackets or supports on which, respectively, the two lower conical rollers are mounted, a spring fastened at one end to a fixed support and a curved tapering block mounted on the free end of said spring and provided with a concave seat at the end thereof adapted to receive the bent portion of said spring-finger and to abut the end of said upper conical roller, said block being located beneath said upper conical roller and between said lower rollers, substantially as specified.

5. In a cigar-machine, the combination of two fixed rotatable main rollers located in the same plane and one rotatable main roller so 110 mounted as to be midway between them in a higher plane, a pivotally-mounted handle adapted to move said upper rotatable main roller from its said position, a spring-rod ex- 115 120 125 130 135

tending from said handle parallel with the axis of the upper main roller, a companion conical roller for each of said three main rollers and connected to the same, respectively, 5 by a ball-and-socket joint, said conical rollers converging at their outer ends, brackets adapted to support the smaller ends of the two lower conical rollers, a finger mounted on the outer end of the spring-rod and having 10 its lower end bent and engaging the outer end of the upper conical roller, a spring fastened at one end to a fixed support and a block mounted on the free end of said spring and

provided with a concave seat adapted to receive the lower bent end of said finger and to 15 abut the outer end of the upper conical roller, said block being located beneath the upper conical roller and between the two lower conical rollers, substantially as specified.

In testimony whereof I affix my signature 20 in presence of two witnesses.

THOMAS E. CARPENTER.
